FLOOR-TO-SIDEWALL CONNECTION
FOR VEHICLES

Walter S. Eggert, Jr., Philadelphia, Pa., assignor to The Budd Company, Philadelphia, Pa., a corporation of Pennsylvania

Filed Feb. 23, 1962, Ser. No. 175,114
3 Claims. (Cl. 105—491)

This invention relates to floor-to-sidewall connections for vehicles, and more particularly to new and improved flexible joint railway vehicle structures.

Railway cars were at one time made of wood, reinforced with steel plates, bolted or riveted together. Wooden cars were replaced with cars made of steel plates bolted and/or riveted together. Modern railway cars are made by welding shapes together to form all-welded or all-steel railway cars. Such railway cars were structurally designed and assembled to form a rigid box.

Recent developments in railway cars have shown that rigid box structures are subject to stress concentrations at the points or joints of intersection of the rigid frame panels, for example, the floor and sidewall panels. Elimination of the rigid intersection between these panels by provision of a flexible intersection structure improves the load-carrying characteristics of the structure and prevents fatigue failures at points of stress concentration in rigid all-steel cars.

Heretofore, flexible intersection joints between intersecting panels were restricted to flexible plates which were load-carrying members. In all-welded, all-steel railway cars flexible plates are acceptable, but flexible plates preclude the assembly and disassembly of car panels once they are welded in place. The flexible plate intersection joint has proven the desirability of further improvements in flexible joints.

Therefore, it is a primary object of the present invention to provide a new and improved friction connection between the floor-to-sidewall of a vehicle which will provide a flexing movement and avoid the heavy stress concentrations typical of rigid joint structures.

Another object of the present invention is to provide a flexible joint construction between the floor-to-sidewall which uniformly transmits and distributes loads imposed on one panel into the adjacent intersecting panel by friction coupling.

A further object of the present invention is to provide a new and improved joint between floor-to-sidewall which permits easy modification of existing rigid joint vehicle structures to provide a new and improved flexible joint structure.

Other features and objects of novelty will be apparent from the following description of an exemplary embodiment, reference being made to the accompanying drawings wherein:

FIG. 1 is a side elevation of a railway car body assembled from side, roof and floor panels;

FIG. 2 is an enlarged sectional elevation taken at the intersection of the floor panel and side panel of the car body of FIG. 1 showing the friction-coupled flexible joint connection of the present invention;

FIG. 3 is a plan view of the coupled spring washer shown in elevation in FIG. 2;

FIG. 4 is a section taken through the spring washer of FIG. 3 showing the washer in its normal unloaded state.

Referring now to FIG. 1 illustrating a typical railway car having a roof panel 10, a side panel 12 and a floor panel 14 (FIG. 2). The floor panel 14 and side panel 12 are joined together at the bottom edge of the side

2

panel and the side edge of the floor panel to form a flexible connection.

Floor panel 14 comprises sandwich panel sheets 16 and a T-beam floor sill 18 welded thereto. The sandwich panel may be formed from low-carbon deep-drawing steel and the T-beam is a commercially available structural shape provided with a laterally extending web.

Side panel 12 comprises a plurality of sidewall posts 20 covered on the outside by corrugations 22 welded thereto. A Z-section formed sidesill plate 24 is attached by its upward extending leg to the sidewall posts 20 by welds as shown. In the preferred embodiment shown, the upward extending leg of the Z-section or sidesill 24 has a formed reinforcing bead and the downward extending leg is turned under to form a channel shaped member, thus, providing a structural reinforcing member for the sidewall posts. The central web of the Z-section sidesill 24 runs horizontal along the bottom of the sidewall posts. An outer plate 26 is connected to the outside of

the sidewall posts 20 and to the downward leg of the Z-section 24.

During the manufacture of the railway car, floor panel 14 and side panel 12 are fabricated as separate components. After the floor panel 14 is erected the side panel 12 is lowered onto the horizontal web of the through-running floor sill 18. Sidesill 24 forms a nesting structure for aligning the sidewall panel 12 onto the floor sill 18. A mastic sealer 28 may be added between the sidewall panel 12 and floor panel 14 as shown.

In order to provide a joint which is flexible and still provide an area of contact between the central web of sidesill 24 and floor sill 18, spring loaded fastening means 30 are employed to connect the sills 18 and 24. To facilitate ease of assembly the web members of the sills 18 and 24 are prepunched to provide an oversize aperture for the fastening means 30. Fastening means 30 preferably comprises a shear bolt 32, a locknut or elastic stop nut 34 and one or more spring loading washers 36 which will be described hereinafter.

The webs of sills 18 and 24 are provided with oversize apertures to eliminate any transmission of shear bearing loads between the web members through the bolt 32. This is a unique departure from rigid all-welded structures and flexible all-welded structures.

When a load is applied to sidewall panel 12 that tends to bend it either outwardly or inwardly, fastening means 30 maintains a portion of the web of sill 24 in contact with the sill 18. If a load tends to bend the sidewall panel 12 outward, the fastening means 30 permits the portion of the web of sill 24 to the right of bolt 32 to lift against the spring tension of washer 36. When panel 12 tends to bend inward, the outer portion of the web of sill 24 to the left of bolt 32 tends to lift against the tension of washer 36. It is apparent from an explanation of the flexing action that the moment forces at the panel joints are greatly reduced.

Not only does the spring action of the washer 36 spread the bending moment imposed at the bolt 32, but the fastening means 30 are spaced between sidewall posts 20 so that the webs of the sills act as torsion bars between adjacent sidewall posts. This is accomplished by spacing the bolts away from the intersection of the side posts and the side sills 24.

FIG. 3 is a plan view of the spring loading washer 36 which is formed by providing a flat blank of metal slightly larger than the outer perimeter of the shaped washer shown. The blank is pressed between mating dies to provide a cupped and arised spring loading washer 36 as shown in FIG. 4. The cupped spring loading washer 36 is heat treated after die forming to provide its spring characteristics. Once the spring loading washer 36 is

3
compressed flush against the sidesill 24 by the nut and bolt the locking action between sills 18 and 24 is by friction alone.

The rail car joint shown offers a cheap reliable flexible joint which permits complete rail cars to be made as panels, shipped in panel form to distant points and assembled without any requirement for factory jigs and expensive equipment. Not only does this reduce the cost of manufacture, but greatly reduces shipping costs. Also, existing rigid joint structures may be disassembled and provide with sills similar to those shown and readily reassembled without employing expensive jigs.

It is seen that the invention provides a very dependable, and durable connection which is easy to assemble. The nesting action of the interconnecting joint of the panels does not attempt to cut through or shear the bolt 32 and provides a novel and improved flexure connection between railway car panels which continue to remain friction tight even though some wear may occur. The novel friction coupled flexible joint permits the employment of materials which are incompatible for welding. While one embodiment of the invention has been described for the purposes of illustration it is to be understood that there may be various embodiments and modifications within the scope of the invention such as minor modifications of the sill elements or the fastening means to achieve the novel flexure joint.

What is claimed is:

1. A flexible floor-to-sidewall connection for a railway vehicle having a vertical sidewall panel and a horizontal floor panel comprising, a vertical sidewall panel having a plurality of vertical sidewall posts, a through-running Z-section sidesill connected to said plurality of sidewall posts, said sidesill having an upturned leg and a downturned leg connected to a center web, bent formations on each said leg providing longitudinal stiffness, a horizontal floor panel having reinforcing skin sheets, a throughrunning T-section sidesill connected to said skin

5
sheets and providing a cantilevered extending horizontal web, a bolt connector fastened through said center web of said Z-section and said horizontal web of said T-section connecting said floor panel to said sidewall panel, and a cupped spring washer flush mounted between said connector and said center web providing a spring loaded flexible joint between said floor panel and said sidewall panel.

10
2. A connection as set forth in claim 1 wherein there is further provided an outside reinforcing plate connected to said sidewall post and to said downward leg of said Z-section.

15
3. In a railway vehicle, the combination comprising: a sidewall panel comprising a plurality of vertical, longitudinally-spaced posts, a sidewall sill connected to and extending along the bottom of sidewall panel, a sandwich structure floor panel, a T-section sill attached to and extending along said floor panel and having a horizontal portion abutting a portion of said sidewall sill along its length, a plurality of cupped spring washers mounted against said sidewall sill at spaced intervals between said posts, said washers and said sills having aligned apertures therethrough, and a plurality of connectors extending through said apertures and compressing said washers against said sidewall sill to bias said sills against each other.
